UNITED STATES PATENT OFFICE

JOSÉ VASTA, OF BUENOS AIRES, ARGENTINA

NOVEL DEVICE TO WAVE THE HAIR AND STEAM CHAMBER TO MAINTAIN THE PERMANENT WAVE OR CURL

Application filed November 16, 1929, Serial No. 407,733, and in Argentina March 20, 1929.

This invention relates to a new and improved apparatus for coiling hair upon a rod or bobbin utilized in the process of providing permanent waves, and to an improved and simplified arrangement of a steam chamber in connection with such rods or bobbins whereby the hair when treated by the heat of the steam will secure a permanent wave capable of maintaining such wave for a long period of time.

A further object of the invention is to provide a tubular body or means for coiling the hair of such simplicity that the preparation of the hair for the permanent waving operation may be carried out by an unskilled person.

An additional object of the invention is to provide a device which can be manufactured at small cost and also to provide a steam chamber for cooperating with the bobbin device of such simplicity that it may also be operated by a person unskilled in the art.

Apparatuses for permanently waving the human hair have been known for a long time and they generally depend to a great extent upon the employment of electricity for heating the hair. The present invention is designed to utilize the heat of steam since results are more rapid and the effects from the process are more permanent. In addition, the utilization of steam eliminates the probabilities of short circuiting with the consequent danger to both the operator and the person operated upon.

In addition, various apparatuses have also been designed to use the heat of steam, but they have not been found practical mainly because of the relatively high cost of manufacture, especially that type wherein electricity and steam both are used. There is also a disadvantage in these devices due to the fact that the hair is submitted directly to the steam or the steam passed into the heating chamber is not permitted to properly evacuate, which causes a difference in temperature between different elements of the device rendering the results highly unsatisfactory. The present invention is designed primarily to overcome the various disadvantages pointed out above.

With these and other objects in view which will become apparent during the course of the following detailed description, the invention consists in the combination and arrangement of parts set forth below, claimed in the claims and shown in the drawings, in which

Figure 1 is a partial elevational view of the coiling apparatus,

Figure 2 is a partial sectional view taken at right angles to Figure 1,

Figure 3 is an elevational view showing the hair coiling device in operation,

Figure 4 shows cross sectional views taken vertically through the steam chamber device,

Figure 5 is an elevational view of the entire device showing the clasp or handle member encircling the same, and

Figure 6 shows an elevational view of the casing adapted to enclose the steam chamber.

Figure 7 is a cross sectional view.

Throughout the drawings similar reference characters indicate like parts.

The coiling apparatus is shown particularly in Figures 1 to 3 and consists of a tubular member 1 having an enlarged portion 2 and a longer and narrower portion 3 which is provided with a partial longitudinal cut-out portion. The cut-out portion has one side 4 thereof bent outwardly in order to form a rectangular projecting plate 7. The plate 7 has pivoted to it at 6 an arc-shaped member 5 which is adapted to cooperate with the edge 4 of the plate 7 to form an eye opening through which the hair may be led.

The plate 7 has provided thereon vertically projecting comb teeth 8 and also horizontally projecting angle members 10 which are apertured at 10" to receive the removable pin 9. A further support 10' in the form of a loop is also provided for the pin 9 adjacent to the upper edge of the plate 7. The construction is such that the inserted pin 9 will form together with the plate 7 and the angle pieces 10 a rectangular opening upon the inner side of the comb teeth 8.

The operation of the coiling apparatus will now be described.

A rod or bobbin 11 (see Figure 3) is first introduced through the large portion 2

through the narrow portion 3 and the end of a lock of hair is secured to the end of the bobbin by the claw or other fastening means 12. The hair is placed over the comb teeth 5 and bent down over the edge 4 of the plate 7. The pin 9 is then inserted and thereafter the arc piece 5 is swung up into position over the edge of the plate so that the lock of hair 13 becomes fixed and when the rod 11 is rotated 10 will become coiled thereon. The arc member 5 is released and the pin 9 loosened, which permits the tubular body 1 to be withdrawn and the rod 11 with the hair coiled thereupon is now ready to be treated in the 15 steam chamber now to be described.

The permanent waving or curling device is shown particularly in Figures 4, 5 and 6 and comprises the steam chamber composed of two semi-circular sections 14 having double 20 walls so as to form the hollow steam spaces 15. The ends and the edges of the cooperating semi-circular sections are air tight which will thus form two separate chambers of sufficient length to receive the rod or bobbin 25 as shown particularly in Figure 4. Each of the two sections 14 is provided at the top and bottom thereof with steam inlet ports 16 and 19 and steam outlet ports 17 and 18 upon which can be secured flexible removable rubber tubes 20 and 21 for the proper regulation 30 of the steam.

The steam can be provided by any convenient generator not shown and the steam enters the inlet 16 upon the left hand chamber section shown in Figure 4 and after having circulated therein will leave this section by the outlet 17 and pass by means of the rubber tube 20 to the inlet 19 upon the right hand chamber section 14 from which it may leave 40 by the outlet 18 to an adjacent chamber by means of a rubber tube or may be evacuated into the atmosphere. It will be noted that a direct circuit is provided for the steam thereby maintaining the temperature throughout 45 the entire device uniform during the treating of the hair.

For insulating purposes the present invention contemplates further the provision of a cylindrical longitudinally divided casing 22 50 of the same length as the chamber sections 14 and provided with apertures 23 adapted to coincide with the steam inlet and outlet ports 16, 17, 18 and 19. The casing is designed to completely embrace the combined steam 55 chamber.

In order to facilitate the handling of the entire device together with the embracing casing 22 and to permit the device to be suspended from a cord secured to any available 60 support, a combined clasp and handle member 24 is shown in Figure 5 of any convenient construction preferably somewhat similar to the clamps or clasps used upon papers.

It is obvious that the operation can be carried 65 out conveniently within fairly wide

limits due to the capacity of the steam chamber to handle different size locks of hair.

It is also obvious that various modifications may be embodied in the invention as disclosed above without departing from the spirit of the present invention and I therefore desire to include all such modifications as may fall within the scope of the following claims.

I claim:—

1. Novel device to wave the hair and steam chamber to maintain the permanent wave or curl, the combination of two longitudinal semi-circular steam chambers, which are provided with steam inlet and outlet pipes, small flexible and removable rubber tubes fitted to said inlet and outlet pipes to conduct the steam from any suitable generator by the inlet of one of the chambers or sections of the combined chamber and, after having passed therethrough, from this by the outlet, rubber tube and inlet to the second section, from which after having circulated therein, it may be permitted to escape by the outlet in order to take the same way through the next curling device, said combined chamber being of sufficient diameter to receive the bobbin with the coiled hair lock.

2. Novel device to wave the hair and steam chamber to maintain wave or curl, the combination of two longitudinal semi-circular steam chambers in connection with a casing of the same length consisting of two semi-circular halves which comprise notches coinciding with the steam inlets and outlets so as to be adapted to embrace the combined chamber, and in connection with a combined clasp and handle member of any convenient construction and formed so as to receive in its interior the combined steam chamber together with the casing of same, to cover and to compress the entire construction facilitating the operating and handling of the curling device.
